UNITED STATES PATENT OFFICE.

ARON M. BEAM, OF DENVER, COLORADO, ASSIGNOR TO THE NATIONAL AUTOMATIC FURNACE MILLS AND MINING COMPANY, OF DENVER, COLORADO, A CORPORATION OF COLORADO.

ORE-ROASTING FURNACE.

SPECIFICATION forming part of Letters Patent No. 745,765, dated December 1, 1903.

Application filed August 30, 1902. Serial No. 121,585. (No model.)

To all whom it may concern:

Be it known that I, ARON M. BEAM, a citizen of the United States of America, residing at Denver, in the county of Arapahoe and State of Colorado, have invented certain new and useful Improvements in Ore-Roasting Furnaces; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in ore-treating furnaces; and the objects of my invention are, first, to provide a revoluble cylindrical muffled furnace; second, to provide an ore-treating muffled furnace that will give to rebellious ores a roast that will convert them to a free-milling condition; third, to provide an automatic ore-treating furnace that will give to ores an oxidizing roast; fourth, to provide a furnace in which the ore is automatically fed through the machine and is automatically rabbled. I attain these objects by the mechanism illustrated in the accompanying drawings, in which—

Figure 1 is a longitudinal side view of my improved ore-treating furnace, partially in section and partially in elevation. Fig. 2 is an enlarged sectional view of the discharge end of the furnace. Fig. 3 is an enlarged sectional view of the feed end of the furnace. Fig. 4 is an end elevation of the discharge end of the furnace. Fig. 5 is an end elevation of the feed end of the furnace. Fig. 6 is a plan view of the feed end of the furnace. Fig. 7 is a plan view of the discharge end of the furnace. Fig. 8 is a cross-section of the furnace on line A of Fig. 1. Fig. 9 is a longitudinal section view of one of the central sections of the furnace, showing the central portion of the section in elevation. Fig. 10 is a longitudinal sectional view of the feed end section of the furnace, showing its central screw-blade in elevation. Fig. 11 is an end elevation of the discharge end of the furnace, showing a dust-chamber attachment connected to

the fume-chimney of the furnace. Fig. 12 is a section of the cylinder, showing the manner of attaching the tread-ring on which the flue-cylinder rolls to it. Fig. 13 is a section of the cylinder, showing the preferred arrangement of the driving-gear. Fig. 14 is a perspective view of one-half of the tread-ring on which the flue-cylinder rests. Fig. 15 is a fragmentary sectional view of a casing I surround the cylinder with, showing the manner of securing the sections of the casing together. Fig. 16 is a plan view of Fig. 15. Fig. 17 is an end elevation of a section, showing a closed cylinder or axial core at the center of the muffled cylinder. Fig. 18 is a fragmentary sectional view of a section of the outer cylinder of the furnace, showing the lugs which hold the inner cylinder in place in the flue-cylinder. Fig. 19 is a sectional view of my furnace, showing a side elevation of my adjustable roller-supports and their foundation bed-plate. Fig. 20 is a fragment of my cylinder, showing an end elevation of the adjustable roller-supports and their end plate. Fig. 21 designates a side elevation of my furnace, partially in section and partially in elevation, showing a furnace provided with an auxiliary combustion-chamber and also with a combined ore-drier arranged in the top of the casing and also with nitrate chambers or tanks and with apparatus for exhausting the sulfurous gases and for converting the sulfurous gases into sulfuric acid. Fig. 22 is a cross-section of Fig. 21 on line B. Fig. 23 is a fragmentary section through the combined ore drier and conveyer on line C of Fig. 21. Fig. 24 is a cross-section on line D of Fig. 21, showing a cross-section through the supplementary combustion-chamber; and Fig. 25 is an end view of the smoke-stack-supporting base, showing the stack-flues arranged to surround the ore drier and conveyer.

Similar figures of reference refer to similar parts throughout the several views.

My improved furnace is composed of two independent concentric cylinders which are detachably secured together, so as to rotate as one cylinder, and which act co-operatively together. Both of these cylinders can be made

in one piece; but owing to their length and the difficulty of transportation in mountainous countries I preferably construct them in sections of a few feet in length.

5 Referring to the drawings, the numeral 1 designates a cylindrical tube which forms the feed end section of the ore-roasting cylinder of my furnace. This cylinder is provided with an integral narrow screw-blade 3, 10 which extends round the inner periphery of the cylinder, thus leaving an axial passage through the cylinder from end to end. 15 4 designates an additional section of the ore-roasting cylinder. This section is secured by bolts 5 to the adjacent end of the feed-section. This section 4 is provided with a series of radial diaphragms or partitions 6, which are preferably spirally-curved partitions, as shown in Figs. 1 and 9, and in section 20 4 and in the central sections of the furnace, although, if desired, they can be made straight, as shown in one of the sections in Fig. 21. The spiral partitions extend practically throughout the entire length of the 25 section with the exception of a narrow portion at each end which is used for securing the section to adjacent sections. Each section in the length of the furnace is provided with these radial partitions. In very 30 large furnaces, where the ore-cylinder is of large diameter, I form a cylindrical space 6^a throughout the center of the ore-cylinder. (See Fig. 17.) This cylindrical space is, however, closed to the ingress of ore, and the 35 cylindrical shell is used to strengthen the diaphragms and to make a larger heating-surface at the cylinder's center, and while I illustrate these partitions arranged spirally through the sections of the cylinder I re- 40 serve the right to arrange them in any suitable order. I arrange from three to six of these radial partitions in each cylinder, depending largely on the diameter of the cylinder, and provide each radial partition with 45 a large number of apertures 7, which, while illustrated round apertures, may be made of any shape. All of the sections of the ore-roasting cylinder are provided with these radial portions except the feed end sections. In 50 the discharge end section, however, the radial partitions terminate at a short distance from the terminal end of the section. The terminal end of this section is closed by a solid integral end portion 8, and the peripheral surface of the end beyond the radial portions throughout its entire circumference is provided with a plurality of apertures 9, through which the ore discharges, as will be fully explained hereinafter. A trunnion 10 55 is formed on the end of the discharge end section, which is supported by a box 11. The box is preferably arranged with a yielding support in order that the terminal end of the ore-cylinder may be free to expand and 60 contract. The trunnion is preferable made hollow, and a cap or plug 10^a is removably threaded to it. The hollow trunnion pro-

vides an opening into the discharge end of the ore-roasting cylinder, through which either air may be admitted or the sulfurous 70 gases be exhausted whenever desired.

The several sections of the cylinder are secured together in any suitable manner, but are preferably provided with stepped or overlapping ends, which are secured together by 75 bolts 12. By this means an ore-cylinder can be built up of any desired length. The outer peripheral surface of each section is provided with three or more radial arms 13, placed equidistant apart in a rotative plane, each of 80 the sections being preferably provided with a set adjacent to each end except the discharge end section, which is provided with preferably but one set. Upon the peripheral edges of these radial arms 13 of each section a cylinder 14, which I term a "flue-cylinder," is mounted concentrically with the axis of the ore-cylinder. This flue-cylinder is enough longer in diameter than the ore-cylinder to form a large flue-space between the 90 two. In order to insure the concentric arrangement of the two cylinders, the periphery of the arm is turned off true in a lathe, and bearing-lugs 15 are formed at points in the inner periphery of the cylinder for the ends 95 of the arms to rest against. Lugs 16 are also formed on each side of the lugs 15, and a stop-lug 17 is formed across the inner end of the bearing-lug. The bearing-lugs and the slot-lugs are arranged, preferably, adjacent to 100 each end of each section, but the stop-lug 17 is arranged only at the head end 18 of each section, as the ore-cylinder sections are inserted into the sections of the outer cylinder from their head ends. The bearing-lugs are 105 preferably finished concentrically with the axis of the cylinder. The peripheral ends of the arms are then turned to fit slidably and closely against the bearing-lugs. The ore-cylinder is thus securely locked in the center of 110 the outer cylinder. The outer cylinder I term the "flue-cylinder." I also make this flue-cylinder in suitable lengths, the central sections being preferably of the same length as the lengths of the ore-cylinder. Each connecting-section of the flue-cylinder is provided 115 with end flanges 18^a, which are bolted together by bolts 18^b. The flanges are preferably turned both on their ends and edges so as to fit tight together. The end sections of 120 the flue-cylinder are shorter than the end sections of the ore-cylinder, as they terminate in a combustion-chamber 19 at the discharge end and in a smoke-stack-supporting casting 20 at the feed end. This casting consists of 125 a base portion that rests on the foundation, and a round top portion into which the end of the flue-cylinder projects loosely a short distance, leaving a smoke-chamber 21 beyond the end of the flue-chamber in the head 130 end casting.

The adjacent end of the ore-cylinder projects beyond the flue-cylinder and close to the end wall of the casting. In the top of

the feed end casting a smoke-outlet 22 and a smoke-stack 23 are placed. A damper 24 is placed in the smoke-stack.

I arrange a feed-pipe 25 in the end of the head end casting which extends into the aperture in the screw-blades of the end section of the ore-cylinder. This tube is provided with a flanged portion 26, which is secured by bolts 27 to the end of the head end casting. This feed-tube contains a screw conveyer 28, the shaft 29 of which is hollow. This shaft extends beyond the screw conveyer and is supported by a reduced portion that forms a bearing at the outer end of the feed-tube for the screw conveyer and its shaft. The bearing at the outer end of the feed-tube is divided and separated into two parts 30 and 31, which are connected by a yoke-shaped portion 32, which is formed to provide a space around and adjacent to the shaft of the screw conveyer. A sprocket-wheel 32^A is secured to the shaft in this space. The end of the hollow shaft in the bearing 31, the sprocket-wheel which is secured to it, together with a washer 32^B, which is placed against the shoulder at the bottom of the feed-chamber 33 of the feed-tube, hold the feed-conveyer and its shaft in rotative position in the feed-tube. A pipe-nipple 34 is threaded into the end of the bearing 31, and a check-nut 35 is threaded to the pipe and is screwed against the hub and locks the nipple to the hub. A valve 36 is secured to the end of the nipple, and a nipple 37 and coupler 38 are secured to the valve. A hose 39 is connected to the coupler and extends to and is connected to a pressure-blower 40, which is operatively connected to a source of power by a belt 40^A.

A hopper 41 is arranged on the top of the feed-tube to discharge into the rear end of its ore-chamber. An ore-hopper 42 is also arranged around the smoke-stack and is secured thereto in order that it may receive heat from it, and a hopper 43 is arranged on the smoke-stack ore-hopper, in which fluxes are placed. The flux-hopper is so arranged that its discharge-outlet empties into the hopper of the feed-tube.

A shaft extends through the discharge end of the ore-hopper, and a suitable feed-roller 44 is rotatively mounted on the shaft 45 in the discharge end of the ore-hopper. The shaft extends beyond the hopper and is provided with a pulley from which a belt 46 extends to a source of power.

The discharge-outlet of the flux-hopper is arranged to discharge into the feed-hopper above the feed-roller, so that the ore and flux mix together and feed together through the feed-roller. A slide 47 is arranged in the discharge-outlet of the flux-hopper by which the flux can be shut off when desired. In the base of the head end casting I place a door 48 to enable the soot that settles in the bottom of the casting to be removed.

At the discharge end of the furnace the ore-cylinder extends beyond the end of the

flue-cylinder and is built into and is surrounded by a discharge-hood 50, which is provided with an ore-discharge chute 51. This 70 discharge-hood is provided with flanged steps 51^A, that rest on the brickwork of the furnace, and with a front flanged frame 51^B, that rests against the ends of the brick walls. A circular opening 52 is formed in the inner side, through 75 which the end of the ore-cylinder projects, a fume or gas outlet 52^C is formed in the top of the hood, and a stack 52^D is connected to the opening. The end of the furnace projects through the chamber of the hood to close to its 80 side, where a hollow hub 53 is formed, through which the trunnion 10 at the end of the ore-cylinder projects. A damper 52^E is placed on the fume-outlet. From the bottom of the hood portion of the chute a discharge-spout 54 extends laterally through the brickwork. A 85 swinging door 55 is placed in the mouth of the spout to prevent cold air from entering the hood.

The combustion-chamber 19 is constructed 90 in the brickwork and is preferably separated from the ore-discharge hood by a brick wall 56. A flange 57 is also formed adjacent to the end of the discharge end of the cylinder, which is arranged close to the dividing-wall 95 between the hood and the combustion-chamber, and a flange 58 is also preferably formed on the hood to extend by the flange on the ore-cylinder. By this method ore-dust is kept from working into the combustion-chamber 100 and the products of combustion are kept from working into the ore-discharge hood. The combustion-chamber 50 is formed by the brick walls to surround the ore-cylinder adjacent to its discharge end. It is provided 105 with fire-grates 59 and a door-frame 60, which is provided with coal-doors 61 and 62 and ash-pit doors 63 and 64.

The brick walls which form the combustion-chamber and support the ore-discharging hood are bound together by tie-bolts 65 and buckstays 66 and the bearing-blocks 67, which are arranged on the four sides of the brickwork. The frame 51^B is clamped by the buckstays at the end of the furnace 115 against the brickwork.

I preferably support the box that supports the trunnions of the ore-cylinder from above and by a swinging support, and in order to accomplish this I make the bearing-block of the tie-rods at the end of the furnace wide enough to receive downwardly-extending bolts 68, the lower ends of which are secured to the box. The upper ends extend above the block and are threaded and provided with 125 nuts 69. Between the nuts of each bolt and the top of the bearing-blocks I place a spring 70. The springs are adapted to support the weight of the end of the ore-cylinder and act as a yielding medium for the axial expansion 130 and contraction of the ore-cylinder, which also is given a little lateral freedom at the extreme end by this arrangement. A ring 71 is preferably built into the rear wall of

the combustion-chamber and is provided with an annular groove 72, into which the end of the flue-cylinder extends loosely, so that it is free to rotate therein.

5 The flue-cylinder rests and rotates on rollers 73. These rollers are arranged to run on the flanges at the opposite ends of the flue-cylinder. The rollers are mounted on shafts 74, which are supported in boxes 75. 10 These boxes are preferably adjustably arranged on a suitable foundation bed-plate 76, although, if desired, they may be fixed to a suitable foundation, as shown in Fig. 21. I preferably arrange boxes, however, in the 15 following manner: The bed-plate 76 is arranged to be bolted to a foundation by bolts 77. The bed-plates are provided with T-slots 78 and with a keyway 79, and the boxes are provided with a depending key portion 80, 20 that fits slidably into the keyway 79 of the bed-plate.

The boxes 75 are provided with bolts 81, the heads 82 of which extend loosely and slidably into the T-slots of the bed-plate. To 25 each box of each bed-plate bolts 83 and 84 are connected, which extend toward each other, the free ends of which are threaded and are connected together by a turnbuckle 85. This adjustable arrangement of the rollers enables 30 either one or both of the rollers to be laterally adjusted in relation to the longitudinal axis of the cylinder to raise or lower the cylinder at either end, and thereby effect its perfect adjustment relative to its fixed feed

35 and discharge ends and also to adjust for unequal settlement of the foundation, which is liable to take place, and which will allow either one or both ends of the cylinder to settle and rub and grind in either one or both 40 of its fixed end connections. This adjustable arrangement of the rollers operates in the following manner: If it is desired to raise either one side or the other and at the same time give a lateral movement to the cylinder, one of the roller's boxes is bolted down 45 tight and the other loosened, and the turnbuckle is manipulated to move the loosened box toward the cylinder, which will raise it or allow the box to move away from the cylinder, which will lower the cylinder.

In case it is desired to raise or lower the cylinder vertically both boxes should be loosened and the turnbuckle manipulated to move the boxes toward or away from each 55 other. After the rollers and their boxes have been moved to effect the desired adjustment of the cylinder they are bolted rigidly to the bed-plate by tightening their bolts 81.

The rollers may bear and run directly on 60 the edges of the flanges of the cylinders for small furnaces, as shown in Figs. 2, 19, and 20; but I preferably provide a special tread-ring for the rollers to run on for furnaces of large capacity, as the weight is very much 65 greater, and as the heat is always high on any size of furnace it is necessary when the weight is heavy to use a special tread-ring designed

with a broad bearing-surface and arranged to keep the high heat of the flanges from the rollers. I preferably carry out this feature 70 of my invention in the following manner: Upon the flanges I wish to use for the roller tread-bearing of the cylinder I mount a ring 86, which I preferably divide into two halves, (see Fig. 14,) in which one of the halves of the 75 tread-ring is illustrated with two side flanges 87 and 88, which extend loosely down over the sides of the flanges of the cylinder, but at a slight space from them, thus leaving an air-space at each side. The inner periphery of 80 the ring is provided with depending lugs 89, which bear on the edge of the flanges which the intermediate portions of the inner periphery do not touch, the edges of the flanges forming air-spaces between the ring and the 85 flanges. These lugs are also provided with air-apertures 90, which extend from the lugs through the periphery of each half of the ring. The ends of each half of the ring are also provided with lugs 91 and 92, which register opposite each other when the two halves are placed on the flanges of the cylinder, as is shown in Fig. 1, and these lugs are provided with bolt-holes and the halves are bolted together by bolts 93 to clamp tightly to the edge 95 of the flanges.

I preferably use gearing for rotating the cylinder, as it is positive in its action, although a pulley and belt or a friction-pulley and pinion could be operatively arranged to 100 rotate it, if desired.

Upon any desired section of the flue-cylinder I secure a gear 94, which is made in two halves and is arranged to be bolted together by bolts 95. Suitable feet 96 are also formed 105 on each half and are bolted to the cylinder by bolts 97. A gear-pinion 98 is arranged to mesh with the gear centrally underneath the cylinder, and I make the teeth of both gear and pinion long, so that a slight adjustment 110 of the cylinder in any direction by its roller-bearings will not bind or disengage them.

The power is secured to a shaft 99, which is supported in suitable boxes 100, which are mounted on a suitable bed-plate 101. The 115 bed-plate 101 is bolted to the foundation. A gear 102 is secured to the shaft 99, and a pinion 103 is arranged to mesh with it. The pinion 103 is secured to a shaft 104, which is supported in a box 105 on the bed-plate 101. This bed-plate is bolted to the foundation by the bolts 101^A. A sprocket-wheel 106 is secured to the shaft 104, and a chain 107 extends from the sprocket to a source of power, which may be arranged to impart several different speeds to the sprocket 106, and consequently to the cylinder.

I arrange the cylinder at a slight incline, the feed end being the highest in order that we may feed naturally as the cylinders rotate 130 toward the discharge end, and preferably arrange for the amount of inclination of the cylinders in the foundations and in the foundation bed-plates, which I make preferably

tapering on their top surfaces, where the roller-boxes are secured. The ore-cylinder is prevented from any slipping movement in the flue-cylinder, due to the inclination 5 of the cylinders, by its radial arms and the stop-lugs in the flue-cylinder, against which its arms rest; but it is necessary to employ some means to prevent the flue-cylinder from working toward the discharge end. I preferably accomplish this by providing one of the central sections of the cylinder with a circumferential ring 108, which may be attached to or may form an integral part thereof, and preferably place the ring adjacent 15 to the driving-gear of the cylinder and arrange on each side of the cylinder vertical arms 109 and 110. I preferably secure these arms to the bed-plate that supports the driving mechanism by the bolts 111 and 112.

20 The top of the vertical arms, which are arranged at substantially the horizontal center of the cylinder, are provided with yoke-shaped ends, through which a pin extends. Upon this pin, between the yoke-shaped ends, I mount a 25 roller, which bears against the adjacent side face of the ring 108, and in order to support the arms against the weight of the cylinder I extend an anchor-bolt 113 from each arm from near their tops forward toward the head 30 end of the cylinder down into the foundation.

In order to retain the heat in the cylinders, I surround them with a casing 114, which may be made of sheet-iron or cast-iron or of any other suitable material. I divide this casing 35 into sections of substantially the same lengths as the cylinders, so as to bring all the joints of these parts of the furnace at the same points. The casing extends from the foundation on which the furnace rests and to which 40 it is secured by bolts 114^A completely around it, and the sections are preferably arranged to overlap each other and are secured together by the bolts 115. These bolts are pivotally attached to one section at one end and swing 45 over into a slotted lug 116, against which the nut 117 of the bolt is tightened, thus bolting the sections together. (See Figs. 1, 8, 15, and 16.)

As some ores are more apt to dust than others in passing through the furnace and as the ore-dust is sometimes valuable, I provide the fume-stack of the ore-discharge hood with a dust-settling-chamber attachment 118. This dust-settling chamber comprises a narrow 55 sheet-iron extension to the fume-stack. The stack is made with a bend and then to extend off at its top side in an angle portion 119 a short distance above the top of the hood and then to again bend and extend in a vertical 60 portion 120 upward as far as is desired. The extension portion 118 extends from the angled offset out even with the vertical portion of the upper end of the stack and with a downward angle portion 121 to a narrow pipe portion 65 which extends into any suitable reception, but preferably into the cooler 122, which receives the hot ore from the furnace. This

cooler is simply a water-jacketed trough 123 with a screw conveyer in it, which is arranged to receive the ore discharged from the spout 70 54 of the furnace and cool it as it is moved through it by the screw conveyer. It does not form any part of my invention.

As some ores are entirely too wet as they come from the pulverizing machinery to be 75 dried by the heat from the smoke-stack that comes in contact with the ore in the hopper that surrounds the stack, it is necessary to provide some means to very thoroughly dry the ore before it is fed into the furnace, and 80 as there is a great deal of heat radiated from the furnace itself I preferably arrange to utilize this heat to thoroughly dry the ore in the following manner: In addition to making the surrounding casing of suitable lengths 85 I also make each section in two parts, separating them at their tops and making each part enough less than a half to form a space in the top of the casing along its entire length. In this slot I place an ore-drier 123^A, preferably arranging it so that it inclines from the discharge end toward the feed end of the furnace. This ore-drier preferably comprises a 90 semicircular or U-shaped trough, in which a screw conveyer 124 is operatively arranged. 95

The shaft of the screw conveyer is mounted in suitable journals 125 and extends beyond the end of the drier at the feed end of the furnace and is supported by a bracket 126, which is secured to the flux-hopper. A 100 cone-pulley 127 is mounted on the shaft and is connected by belt to a suitable source of power. This enables several rotative speeds to be given to the screw.

As the ore-drier inclines in one direction 105 and the furnace inclines in the opposite direction it is necessary to provide the sides of the ore-conveyer with depending side flanges 128 and 129, which extend down into the slot in the top of the casing, from these depending flanges. Lateral flanges 130 and 131 extend, which lap over and rest on the both halves of the casing and are secured to them by bolts 132. (See Figs. 21, 22, and 23.) By this arrangement the heat which radiates 110 from the flue-cylinder rises into direct contact with the bottom of the ore-drier. Thus the ore travels through a high heat substantially the whole length of the furnace. A small flue 133 can also be made, if desired, 115 in the wall 134 of the combustion-chamber into the space between the flue-cylinder and the casing. A discharge-spout 135 extends from the discharge end of the ore-drier into the hopper 41 of the ore-feeding device of the 120 furnace.

I preferably place a hopper 137 at the head 125 end of the drier, into which the ore is fed. In order to arrange the drier centrally in the top of the casing, it is necessary to provide 130 the smoke-stack supporting or base casting 20 of the furnace with two separated flues 138 and 139, extending from its top, and to arrange them to form a central opening be-

tween them, through which the ore-drier extends. These two flues then unite into one flue above the drier, and the smoke-stack 23 is connected to the top of the flue.

5 Furnaces of large capacity are necessarily long and may vary from thirty-five to sixty feet in length, and for the long furnaces I employ an additional or supplementary combustion-chamber 140, which I position at a 10 suitable distance from the feed end of the furnace. This combustion-chamber is preferably constructed of brick and surrounds the flue-cylinder and is built between the casing and the flue-cylinder (see Figs. 21 15 and 24) and may be made much smaller than the combustion-chamber at the discharge end of the furnace. It is provided with grates 141 and fuel-doors 142 and ash-pit doors 143. Where oil can be obtained, I prefer it as a 20 fuel to coal or wood, as it gives a long flame, and in case it is used the grates need not be employed.

The flue-cylinder is provided at that portion that passes through the supplementary 25 combustion-chamber with a number of apertures 144, arranged equidistant apart around its circumference. The products of combustion flow through these apertures as the cylinder rotates into the flue-cylinder and surrounds the ore-roasting cylinder and flows to 30 the stack, and thus heat the ore at the feed end much hotter and more quickly than the main combustion-chamber is capable of doing.

As some sulfid ores contain a large percentage of sulfur, which is liberated in my 35 furnace and normally flows to waste from the stack of the ore-discharge hood, and as this sulfur can be saved and be very easily converted into sulfuric acid with but very little 40 expense and can be made an element of value, (especially if the ore is a copper ore and it is desired to extract the copper with solutions after roasting the ore, as sulfuric acid is one of the principal chemicals of the solutions 45 used in the extraction of copper,) I arrange each furnace so that a sulfuric-acid-making apparatus can be readily attached and the sulfur be readily withdrawn from the furnace and converted into sulfuric acid. I preferably carry out this feature of my invention 50 as follows: I remove the cap 10^A from the hollow trunnion of the ore-discharge end of the ore-cylinder and extend a pipe 145 through it into the cylinder. This pipe is 55 supported by a bracket 146, which I secure to the front of the hood by the bolt 147. The pipe 145 extends to an exhaust blower or fan 148, which is connected operatively to a source of power by a belt 149. From the 60 exhaust-fan a pipe leads to a lead-lined tank 150, into which a pipe 151 is also extended. This pipe leads to a supply of steam. In the bottom of the tank several inches of water are placed. Two additional tanks 152 and 153, 65 similar to the tanks 150, are connected by pipes 154 and 155 together. A filter-tank 156 is connected by a pipe 157 with the tank

153, and a valve-controlled pipe 157^A is placed in the bottom of the filter-tank to draw from it the sulfuric acid. The sulfurous gases are 70 exhausted by the exhaust-fan from the ore-cylinder and flow into the tank, into which steam is also constantly flowing from the pipe 151, which precipitates the sulfurous gas into the water, with which it forms sulfuric acid. This flows from one tank to the other and is filtered, and the acid is drawn from the filter. This system of tanks is commonly used in the art of making sulfuric acid and does not form any part of my invention. 80

The operation of my improved ore-treating furnace is as follows: The furnace is heated by the products of combustion passing into the flue-cylinder and surrounding the ore-cylinder. The heat used varies from 500° to 85 1,000° Fahrenheit and generally does not exceed 600°. The flue-cylinder is rotated by the gear-driving mechanism connected to it and the ore-cylinder which is attached to it. The ore is fed into the hopper 41 of the feed 90 device of the furnace and is fed in the furnace by the screw 28, which is rotated by the sprocket-wheel 32^A. The ore drops from the discharge end of the feed device into the screw-blades of the first section of the cylinder, and the cylinders are rotated in a direction that will cause the screw of the first section of the ore-cylinder and also the spirally-arranged partitions of the other sections to 95 feed the ore as it is moved by the rotative movement of the cylinder into and toward the discharge end of the cylinder, and as the cylinders are also inclined downward from the feed end to the discharge end the ore feeds from the screw of the first section into 105 the spaces between the partitions and through the furnace. The partitions carry the ore up as the cylinder rotates, and as the ore runs down toward the center of the furnace it drops through the holes in the partitions and 110 falls onto the next partition below. The ore is thus very thoroughly rabbled and is very evenly exposed to the heat and evenly roasted. As the ore travels toward the discharge end of the furnace the heat increases, and it roasts 115 gradually and discharges through the apertures 9 at the discharge end into the discharge-hood and out through the spout 54 into the cooler 122, and the sulfur, arsenic, antimony, and other deleterious elements in 120 the ore are volatilized and flow also out of one cylinder into the hood and through the stack to the atmosphere. In case, however, it is desired to save the sulfurous gases and 125 convert them into sulfuric acid, then the exhaust-fan and its connecting-pipes and the tanks illustrated in Fig. 21 are attached. While the ore is feeding through the furnace and is roasting a steady volume of air is forced into the ore-chamber at the feed end 130 by the air-pressure fan 40, which forces air through the hose and hollow shaft of the feed-screw of the ore-feeding device at the feed end of the furnace. Thus a supply of oxygen

is continuously furnished that oxidizes the ores and makes an oxidizing roast. In extremely long furnaces if the supply of air admitted at the feed end is not sufficient for the requirement of the ore at the discharge end the exhaust for withdrawing the sulfur can be replaced by an air-pressure fan or blower and a supply of air forced into the ore-cylinder from the discharge end also.

10 Some ores roast much better if a flux is mixed with them, while other ores will roast nicely without a flux. Any of the commonly used roasting-fluxes may be used with this furnace. The ores in passing through this 15 furnace are muffled from contact with the products of combustion from the combustion-chamber.

The sulfids are converted by the roast to soft friable soluble sulfates, which are easily 20 soluble in solutions, and also to oxids. The gold will drop down metallic gold and can be readily saved by amalgamation. The silver, if the heat is not carried above 700°, will remain as an oxid or a low sulfid and can also 25 be saved by amalgamation. If, however, the heat is carried much above 700° Fahrenheit, the silver will pass to a sulfate and then can be saved by leaching with suitable solutions. The copper and zinc will pass to sulfates, and 30 they can be saved by leaching with suitable solutions.

Having described my invention, what I claim as new, and desire to secure by Letters Patent, is—

35 1. In an ore-treating furnace, the combination of a combustion-chamber, a stack-chamber, and a revoluble roasting-cylinder comprising an ore-cylinder and a flue-cylinder surrounding said ore-cylinder, said flue-cylinder communicating with said combustion-chamber and stack-chamber and said ore-cylinder extending through said combustion-chamber.

40 2. In an ore-treating furnace, the combination with the combustion-chamber, of an ore-cylinder passing through said combustion-chamber, a flue-cylinder surrounding said ore-cylinder and secured rotatably thereto and extending from said combustion-chamber, a 45 suitable support at the opposite end of said flue-cylinder, a stack in said support, means for feeding ore into said ore-cylinder, and means for rotating said cylinder.

45 3. In an ore-treating furnace, the combination of a combustion-chamber, a stack-chamber, and a revoluble roasting-cylinder comprising an ore-cylinder and a flue-cylinder surrounding said ore-cylinder, said flue-cylinder communicating with said combustion-chamber and stack-chamber and said ore-cylinder extending substantially through said stack-chamber.

50 4. In an ore-treating furnace, the combination with a combustion-chamber, of an inclined ore-cylinder extending into said combustion-chamber, a flue-chamber connected to said combustion-chamber and arranged to

form a flue for the products of combustion round the ore-cylinder, means, for removably securing said ore-cylinder to said flue-cylinder, a stack arranged in operative relation to said flue-cylinder and combustion-chamber, means including gearing for rotating said cylinders and means including a screw for feeding ore into said ore-cylinder, substantially as described.

5. In an ore-treating-furnace the combination with a combustion-chamber, of a flue-cylinder rotatively mounted in communication with said combustion-chamber, an ore-roasting cylinder axially mounted in said flue-cylinder and extending through said combustion-chamber, means including radial arms for removably securing said ore-roasting cylinder in said flue-cylinder, a stack in operative relation to said flue-cylinder, means for feeding ore to said roasting-cylinder and means for rotating said flue-cylinder, substantially as described.

6. In an ore-treating furnace, the combination with a combustion-chamber, of a flue-cylinder rotatably mounted and connected at one end with said combustion-chamber, a stack at the opposite end of said flue-cylinder, an ore-roasting cylinder centrally supported in said flue-cylinder and projecting beyond it at each end extending through said combustion-chamber, an ore-feeding tube extending into the opposite end of said ore-cylinder from said combustion-chamber comprising a hollow shaft in said tube, a screw conveyer on said shaft, a hopper on said ore-feeding tube connecting with said screw conveyer and means for rotating said shaft and screw, means including an air-blower for forcing air through said shaft into said ore-cylinder, substantially as described.

7. In an ore-treating furnace, the combination with a combustion-chamber and a smoke-stack, of a flue-cylinder rotatably mounted and connected with said combustion-chamber, an ore-roasting cylinder axially arranged in said flue-cylinder, a screw-blade in the inner periphery of the feed end of said ore-cylinder and a plurality of partitions extending from the screw-blade through said ore-cylinder to its discharge end, means for feeding ore into said ore-cylinder, means for discharging ore from said ore-cylinder, and means for rotating both the flue and the ore cylinder, substantially as described.

8. In an ore-treating furnace, the combination with the combustion-chamber, the flue-cylinder rotatively mounted therein, and the stack, of an ore-treating cylinder axially secured in said flue-cylinder to rotate therewith, means within said ore-treating cylinder and including longitudinal partitions for rabbelling the ore, means including a screw conveyer for feeding ore into said ore-cylinder, and ore-discharge apertures in the discharge end of said ore-treating cylinder, substantially as described.

9. In an ore-treating furnace, the combina-

- tion with the combustion-chamber, the flue-cylinder rotatively mounted and the stack, of an ore-treating furnace axially supported in said flue-cylinder and provided with a plurality of spirally and longitudinally arranged partitions, numerous apertures through said partitions, means including a hopper for feeding ore into said ore-cylinder, means including discharge-apertures for discharging ore from said cylinder, means including an air-blower for admitting air into said ore-cylinder, and means for rotating said flue-cylinder and said ore-cylinder, substantially as described.
15. In an ore-treating furnace, the combination with a combustion-chamber, of a flue-cylinder at one end of said combustion-chamber, a stack arranged at the opposite end of said flue-cylinder from said combustion-chamber, means including supporting-rollers for rotating said cylinder, an ore-roasting cylinder axially supported in said flue-cylinder having its discharge end in operative relation to said combustion-chamber, a rabbling device comprising radial members in said ore-roasting cylinder, an ore-feeding device comprising a conveyer extending into the feed end of said ore-roasting cylinder, means including an air-blower and a pipe extending into said ore-roasting cylinder for delivering air into said ore-roasting cylinder, and means for discharging ore from said ore-treating cylinder, substantially as described.
20. In an ore-treating furnace, the combination with the combustion-chamber and the stack, of a flue-cylinder operatively connected to said combustion-chamber and said stack, an ore-roasting cylinder removably secured in the center of said flue-cylinder having spirally-arranged radial members within it, an ore-feeding tube extending into said ore-roasting cylinder containing a hopper and an ore-conveyer, a suitable support for the discharge end of said ore-roasting cylinder, a hood surrounding the discharge end of said ore-roasting cylinder, means for discharging ore from the discharge end of said ore-roasting cylinder into said hood and means for rotating said cylinders, substantially as described.
25. In an ore-treating furnace, the combination with the combustion-chamber and the stack, of a flue-cylinder comprising connected sections of predetermined lengths, of an ore-roasting cylinder removably secured in the center of said flue-cylinder, and composed of connected sections of predetermined lengths, means including supporting-rollers and gearing for rotating said cylinders, means including an ore-conveyer extending into said ore-roasting cylinder for feeding ore into said ore-roasting cylinder, a hood surrounding the discharge end of said ore-roasting cylinder, means for discharging ore into said hood, a trunnion on the discharge end of said cylinder and an automatically-adjustable support for said trunnion, substantially as described.
30. In an ore-treating furnace, the combination with the combustion-chamber and the stack, of a flue-cylinder comprising connected sections of predetermined lengths operatively connected to said combustion-chamber and stack, and an ore-roasting cylinder removably secured in said flue-cylinder and comprising connected sections of predetermined lengths a rabbling device comprising perforated radial members in said ore-treating cylinder, an ore-conveyer arranged to feed ore into said ore-roasting cylinder, a yielding support for the discharge end of said ore-treating cylinder, means including discharge-outlets for discharging the ore from said ore-roasting cylinder and means including supporting-rollers and gearing for rotating said cylinders, substantially as described.
35. In an ore-treating furnace, the combination with the combustion-chamber and the stack, of a flue-cylinder revolvably mounted extending into said combustion-chamber and connected to said stack, adjustable rollers arranged to support said flue-cylinder revolvably, means including gearing for rotating said flue-cylinder, and an ore-roasting cylinder secured in the center of said flue-cylinder provided with perforated radial partitions extending lengthwise through it, substantially as described.
40. In an ore-treating furnace, the combination with the combustion-chamber and the stack, of a flue-cylinder comprising connected sections of predetermined lengths and operatively connected to said combustion-chamber and stack, adjustable rollers arranged to support said flue-cylinder revolvably, a suitable support for said rollers, means including gearing for rotating said flue-cylinder, an ore-roasting cylinder comprising connected sections of predetermined lengths secured in said flue-cylinder, perforated radial partitions in said ore-treating cylinder at its central portion, a screw portion at its feed end, a cylindrical portion at its discharge end containing peripheral discharge-apertures, a hood surrounding said discharge end, a trunnion extending from the discharge end of said ore-roasting cylinder and a bearing-box supporting said trunnion and the discharge end of said cylinder and arranged with a yielding support whereby said box can yield to the expansion and contraction of the discharge end of said ore-roasting cylinder, substantially as described.
45. In an ore-treating furnace, the combination of a combustion-chamber and a stack, with a revoluble flue-cylinder connected at its opposite ends to said combustion-chamber and stack and comprising a plurality of cylinder-sections secured together, suitable roller-supports for said cylinder, an ore-roasting cylinder in said flue-cylinder, a sectional casing arranged to inclose said flue-cylinder at a short space from it and means including a conveyer for feeding ore into and means in-

cluding a chute for discharging ore from said ore-roasting cylinder, substantially as described.

17. In an ore-treating furnace, the combination of a combustion-chamber and a stack, with a revoluble flue-cylinder connected to said source of heat and stack, an ore-roasting cylinder secured in the central portion of said flue-cylinder, having its discharge end 5 extending through and beyond said flue-cylinder and said source of heat, a flexible swinging support for the discharge end of said ore-roasting cylinder, ore-discharge apertures in the discharge end of said ore-roasting cylinder, means for preventing the heat from entering said ore-discharge apertures and means including a tube extending into the opposite end of said ore-roasting furnace for feeding ore to said ore-roasting furnace and means 10 including a tube and an air-blower for forcing air into said ore-roasting cylinder, substantially as described.

18. In an ore-roasting furnace the combination of a combustion-chamber with a revoluble flue-cylinder operatively connected at one of its ends with said combustion-chamber, a stack operatively connected to the opposite end of said flue-cylinder, a support for said stack, a suitable connection between said 25 stack's support and the connecting end of said flue-cylinder, an ore-roasting cylinder axially secured in said flue-cylinder, provided with substantially diametrically-arranged perforated partitions spirally arranged axially of said ore-roasting cylinder, an ore-feed tube secured to said stack-support and extending into said ore-roasting cylinder, a screw conveyer in said tube provided with a hollow shaft, means for rotating said screw conveyer 30 and shaft, and an air-blower operatively connected to said hollow conveyer-shaft, substantially as described.

19. In an ore-treating furnace the combination of a combustion-chamber and a smokestack, with a revoluble flue-cylinder connected to said combustion-chamber and stack, an ore-roasting cylinder extending through said flue-cylinder, an ore-feeding device comprising an ore-conveyer arranged to feed ore into 45 said ore-roasting cylinder, a hopper arranged on said ore-feeding device connecting with said conveyer, an ore-drier, a flux-hopper connected to said drier and arranged to discharge into the discharge-outlet of said drier, 50 and a rotary feed-regulating device arranged to feed the ore and flux together into the hopper of the ore-feeding conveyer of said ore-roasting furnace, substantially as described.

20. In an ore-treating furnace, the combination with a combustion-chamber and a stack, of a flue-cylinder connected to said combustion-chamber and stack, an ore-roasting cylinder secured in said flue-cylinder, a casing surrounding said flue-cylinder, means 55 including rollers and gearing for rotating said cylinders, an ore drier and conveyer arranged along the top of said casing and an ore-feed-

ing device connected to said ore drier and conveyer arranged to receive ore from said ore drier and conveyer and feed it into said 70 ore-roasting furnace, substantially as described.

21. In an ore-treating furnace, the combination with the combustion-chamber and the stack, of a stack-supporting casting, an ore-roasting cylinder comprising connected sections extending through said combustion-chamber and into said stack-supporting casting, radial arms on said ore-roasting cylinder, a flue-cylinder surrounding said ore-roasting 75 cylinder, and connected with the said combustion-chamber and adapted to form a flue round said ore-roasting cylinder, longitudinal lugs on the inner periphery of said flue-cylinder adapted to receive between them the 80 ends of the radial arms of said ore-roasting cylinder and transverse stop-lugs adjacent to said longitudinal lugs arranged and adapted to prevent endwise movement of said ore-roasting cylinder in said flue-cylinder, substantially as described.

22. In an ore-treating furnace, the combination of a combustion-chamber and a stack, with a flue-cylinder comprising connected sections of predetermined lengths and connected with said combustion-chamber and stack, an ore-roasting cylinder comprising connected sections of similar lengths, a flue-cylinder 95 removably secured in said flue-cylinder and of enough smaller diameter to form a flue-space between it and the inner periphery of said flue-cylinder, an ore-feeding conveyer arranged to feed ore into one end of said ore-roasting cylinder, means including a blower and a pipe for introducing air into said ore-roasting cylinder, means including apertures for discharging ore from said ore-roasting cylinder, a casing surrounding said flue-cylinder and provided with a longitudinal space in 100 its top portion, a combined ore conveyer and drier arranged in the space in said casing and arranged to discharge into the ore-feeding conveyer of said ore-roasting cylinder, and means including gearing for rotating said cylinder, substantially as described.

23. In an ore-treating furnace, the combination with a combustion-chamber and a stack, of a revoluble flue-cylinder connected to said combustion-chamber and stack, and comprising cylindrical sections of predetermined 115 lengths provided with flanges at their ends, an ore-cylinder within said flue-cylinder and extending through said combustion-chamber, rollers arranged to revolvably support said flue-cylinder, suitable supporting-boxes for 120 said rollers, a bed-plate for the supporting-boxes of said rollers and means including an adjustable connection between the supporting-boxes of said rollers for adjusting said rollers to raise or lower said flue-cylinder, substantially as described.

24. In an ore-treating furnace, the combination with the combustion-chamber and the stack, of a flue-cylinder revolvably connected

to said combustion-chamber and stack, and comprising cylindrical sections of predetermined lengths provided with flanged ends secured together, a tread-ring secured to a predetermined member of the flanges of said flue-cylinder provided with introverted lugs arranged to bear at several points equidistant in the circumference of said lugs and provided with receding peripheral portions between said introverted lugs adapted to form air-spaces, substantially as described.

25. In an ore-treating furnace, the combination with the combustion-chamber and the stack, of a flue-cylinder revolvably connected to said combustion-chamber and stack, and comprising cylindrical sections of predetermined lengths provided with flanged ends secured together, a tread-ring secured to a predetermined member of the flanges of said flue-cylinder arranged with introverted lugs arranged to bear at several points equidistant in the circumference of said lugs and provided with receding peripheral portions between said introverted lugs adapted to form air-spaces and having radial apertures extend from said introverted lugs through said tread-rings, substantially as described.

26. In an ore-treating furnace, the combination with the combustion-chamber and the stack, of a flue-cylinder revolvably connected to said combustion-chamber and stack, and comprising cylindrical sections of predetermined lengths provided with flanged ends secured together, a tread-ring secured to a predetermined member of the flanges of said flue-cylinder arranged with introverted lugs arranged to bear at several points equidistant in the circumference of said lugs and provided with receding peripheral portions between said introverted lugs adapted to form air-spaces and having radial apertures extend from said introverted lugs through said tread-rings, supporting-rollers arranged under each opposite side of said cylinder, supporting-boxes for said rollers, a bed-plate for said boxes, a guide-slot in said bed-plate, a tongue on each of said boxes fitting into said guide-slot, T-slots in said bed-plate, clamping-bolts extending from said roller-supporting boxes into said T-slots, a bolt secured to each of said roller-supporting boxes and extending toward each other and provided with threaded ends, and a turn-buckle threaded to the ends of said rods and means including gearing for rotating said cylinder, substantially as described.

27. In an ore-treating furnace, the combination with the combustion-chamber and the stack, of a flue-cylinder rotatably mounted in said combustion-chamber and stack, an ore-roasting cylinder secured in said flue-cylinder and extending beyond it at its discharge end through said combustion-chamber and having a closed end, a hollow trunnion on the end of said ore-roasting cylinder, a cap or plug removably secured to said hollow trunnion, a bearing-box mounted on said trun-

nion, a support above said box attached to said furnace, depending rods secured to said support at one end and at their opposite ends to said bearing-box, suitable springs arranged on said rods above said support, whereby said bearing-box is yieldingly supported, substantially as described.

28. In an ore-roasting furnace, the combination with the revoluble flue-cylinder, of a combustion-chamber formed at one extremity thereof and arranged to permit the products of combustion to pass through said flue-cylinder, a suitable smoke-stack operatively connected to the opposite end of said flue-cylinder, an ore-roasting cylinder secured in the center of said flue-cylinder provided with perforated spirally-arranged radial partitions and having said ore-roasting cylinder of enough smaller diameter to allow the products of combustion of said combustion-chamber to surround it as they pass through said flue-cylinder and having said ore-roasting cylinder arranged to receive ore at the stack end of said furnace and to discharge ore at the combustion end of said furnace and having its discharge end extend beyond the end of said flue-cylinder and through and beyond said combustion-chamber, a hood arranged to surround the discharge end of said ore-roasting cylinder, a trunnion on the end of said ore-roasting cylinder, a supporting bearing-box on said trunnion, a support above said bearing-box, rods extending through said support and secured at one end to said bearing-box and extending above said support, nuts on the upper end of said rods and a spring on each rod between said nuts and said support whereby said trunnion bearing-box and the discharge end of said ore-roasting cylinder is yieldingly supported, substantially as described.

29. In an ore-treating furnace the combination with the flue-cylinder and the ore-roasting cylinder extending through said flue-cylinder, of a stack at one end of said flue-cylinder, a combustion-chamber at the opposite end of said flue-cylinder constructed to inclose the discharge end of said ore-roasting cylinder and positioned adjacent to the end of said flue-cylinder, a hood surrounding the end of said ore-roasting cylinder and means including a flange formed on said ore-roasting cylinder and a partition between said combustion-chamber and said hood, for preventing the products of combustion from passing to the discharge end of said cylinder, ore-discharge apertures arranged in the end of said ore-roasting cylinder to discharge into said hood, and a spout arranged on said hood to convey said ore away from said ore-roasting cylinder, substantially as described.

30. In an ore-treating furnace, the combination with the revoluble flue-cylinder, the combustion-chamber and the smoke-stack, of the ore-roasting cylinder centrally secured in said flue-cylinder and extending beyond said flue-cylinder and through and beyond said

combustion-chamber, a hood built into and secured to said combustion-chamber and arranged to surround the end of said ore-roasting cylinder, means including tie-rods and buckstays for binding said combustion-chamber and said hood together, a closed head end at the extreme end of said ore-roasting cylinder, ore-discharge apertures in the periphery of the end of said ore-roasting cylinder arranged to discharge ore into said hood, an ore-discharging spout extending from said hood beyond said combustion-chamber and means including a partition for separating said hood from said combustion-chamber, substantially as described.

31. In an ore-treating furnace, the combination with the flue-cylinder and the stack, of the ore-roasting cylinder extending through said flue-cylinder, a combustion-chamber arranged to surround the discharge end of said ore-roasting cylinder, a hood surrounding the end of said ore-treating cylinder and built into said combustion-chamber, means including tie-rods and buckstays for securing said hood and said combustion-chamber together, an aperture on said hood opposite the end of said ore-roasting cylinder, a trunnion on said ore-roasting cylinder extending through said aperture, a block projecting from the top of said hood and combustion-chamber, means including said tie-rods for securing said block to said hood and combustion-chamber, a journal-box arranged on said trunnion to revolvably support the adjacent end of said ore-roasting cylinder and bolts secured at one end to said box and extending vertically up through said projecting block, a coiled spring in each bolt resting on said block and a nut on each bolt resting on each spring whereby said trunnion journal-box and the discharge end of said ore-roasting cylinder is swingingly and yieldingly supported, substantially as described.

32. In an ore-treating furnace, the combination with a revolvable flue-cylinder, of an ore-roasting cylinder secured within said flue-cylinder to rotate therewith, the diameter of the ore-roasting cylinder being enough smaller than that of the flue-cylinder to form an annular flue space or chamber between the two, a combustion-chamber connected at one end to said flue-cylinder, a stack connected at its opposite end, a supplementary combustion-chamber arranged to surround said flue-cylinder adjacent to said stack and suitable flue-apertures through the periphery of said flue-cylinder registering with said supplementary combustion-chamber, substantially as described.

33. In an ore-treating furnace, the combination with the revolvable flue-cylinder, of an ore-roasting cylinder of smaller diameter than the said flue-cylinder, extending centrally through said flue, a combustion-chamber connected at one end of said flue-cylinder, a stack at the opposite end, and a supplementary combustion-chamber arranged to surround

said flue-cylinder, flue-apertures in the periphery of said flue-cylinder arranged to communicate with said supplementary combustion-chamber, means for revolving said flue-cylinder, means for feeding ore into said ore-roasting cylinder at the stack end of said furnace and means for discharging ore at the combustion end of said furnace, substantially as described.

34. In an ore-treating furnace, the combination with the revolvable flue-cylinder, of an ore-roasting cylinder of smaller diameter than the said flue-cylinder, extending centrally through said flue, a combustion-chamber connected at one end of said flue-cylinder, a stack at the opposite end, and a supplementary combustion-chamber arranged to surround said flue cylinder, flue-apertures in the periphery of said flue-cylinder arranged to communicate with said supplementary combustion-chamber, means for revolving said flue-cylinder, and a casing surrounding said cylinders, means for feeding ore into said ore-roasting cylinder at the stack end of said furnace and means for discharging ore at the combustion end of said furnace, substantially as described.

35. In an ore-treating furnace, the combination with the combustion-chamber, the stack and the flue and ore-roasting cylinders arranged at an inclination from the feed end down toward the discharge end of said cylinders, a flange on said flue-cylinder, a vertical arm secured to a suitable foundation and arranged on each side of said flue-cylinder, a roller pivotally mounted in the top of each arm in bearing engagement with said flange and an anchor-bolt secured at one end to each arm and extending toward the feed end of said cylinder and secured to a suitable foundation at its opposite end whereby a bearing is provided for the end thrust of said cylinders, substantially as described.

36. In an ore-treating furnace, the combination of the rotatable flue-cylinder, the combustion-chamber, the flue-cylinder connected at one end therewith and the stack, with the muffled ore-treating cylinder secured in the center of said flue-cylinder, an annular flue-space between the outer periphery of said ore-roasting-cylinder and the inner periphery of said flue-cylinder, means including perforated spiral blades or partitions for rabbling and feeding ore through said muffled ore-roasting cylinder, means including an ore-conveyer secured to said stack for feeding ore into said muffled ore-roasting cylinder, means for discharging ore from said muffled ore-roasting cylinder, a casing surrounding said flue-cylinder, means including an ore-conveyer arranged in said casing to communicate with the interior thereof and with said ore-feeding device of said muffled cylinder for drying ore and feeding it to said muffled ore-roasting cylinder, substantially as described.

37. In an ore-treating furnace the combination with the ore-roasting cylinder, the com-

- bustion-chamber and the stack, of a casing comprising two arched half portions surrounding said cylinders constructed in sections of predetermined lengths, means including pivotally-swinging clamping-bolts for securing said sections together, an open space between said half portions of said casing over said cylinders, an ore-feeding trough fitting in said space and secured to said sections and 5 extending axially over said cylinders, a screw conveyer operatively mounted in said conveyer, means including a cone-pulley attached to said screw conveyer for imparting various speeds to said conveyer, and means 10 including a spout and an ore-conveyer connected with said ore-roasting cylinder for conveying ore from the conveyer in the top of said casing into said ore-roasting cylinder, substantially as described.
- 15 38. In an ore-treating furnace, the combination with the combustion-chamber and the flue-cylinder, the ore-roasting cylinder projecting through said flue-cylinder and said combustion-chamber and the stack, of a chamber or hood adjacent to said combustion-chamber into which the discharge end of said ore-roasting cylinder extends, discharge-apertures in the end of said ore-roasting cylinder arranged to discharge ore into said chamber or hood, an ore-discharge spout leading 20 from said chamber or hood, a stack connected to the top of said chamber or hood arranged to convey the gases and fumes from said ore-roasting cylinder to the atmosphere, a dust chamber formed in said stack and a depending spout leading from said stack to a suitable receptacle, substantially as described.
- 25 39. In an ore-treating furnace the combination with the combustion-chamber, the flue-cylinder, the ore-roasting cylinder extending through said flue-cylinder, and the stack, of a chamber or hood formed round the discharge end of said ore-roasting cylinder, a gas and fume and dust stack at the top of said chamber or hood extending vertically above said furnace, a bend in said stack, an angled portion in said stack extending from said bend, a second bend in said stack, a vertical portion 30 extending from said second bend, a laterally-extending dust-chamber formed integral with said angled portion of said gas and dust stack, and a discharge-spout extending from said dust-chamber to a suitable receptacle, substantially as described.
- 35 40. In an ore-treating furnace, a revoluble roasting-cylinder having a trunnion at one end, means for heating said cylinder externally, and a depending trunnion-support constructed to move longitudinally with the trunnion as the cylinder expands or contracts.
- 40 41. In an ore-treating furnace, a revoluble roasting-cylinder having a trunnion at one

end, means for heating said cylinder externally, and a depending trunnion-support, comprising flexible rods, constructed to move 65 longitudinally with the trunnion as the cylinder expands or contracts.

42. In an ore-treating furnace, a revoluble roasting-cylinder, having a trunnion at one end, and a depending vertically-resilient 70 trunnion-support.

43. In an ore-treating furnace, the combination of a combustion-chamber, a circular opening in said chamber, a flue-cylinder extending at one end into the opening in said combustion-chamber, rollers arranged to support said flue-cylinder, means including gearing for rotating said cylinder, a stack-supporting casting at the opposite end of said flue-cylinder, a stack connected with said 80 supporting-casting, an ore-roasting cylinder secured in said flue-cylinder, an ore-feeding conveyer secured to said stack-supporting casting and extending into said ore-roasting cylinder, and an ore-drier arranged to 85 receive the heat from said flue-cylinder and said smoke-stack, and to discharge into said ore-feeding device, substantially as described.

44. In an ore-treating-furnace, the combination with the combustion-chamber, the 90 stack, the flue-cylinder, and the ore-roasting cylinder, extending through the combustion-chamber, of a pipe extending into said ore-treating cylinder and its discharge end, a suction or exhaust blower or fan secured to said 95 pipe and arranged to exhaust the sulfurous gases and the fumes from said ore-roasting cylinder, and a pipe leading from said exhaust-blower to a condensing-tank, substantially as described.

45. In an ore-treating furnace, the combination with the combustion-chamber, the stack, the flue-cylinder, and the ore-roasting cylinder, extending through the combustion-chamber, of a hollow trunnion on the discharge end of said ore-roasting cylinder, a pipe extending through said hollow trunnion into said ore-roasting cylinder, means for supporting said pipe in operative position in said trunnion, an exhaust blower or fan connected to said pipe, arranged and adapted to exhaust sulfurous gases from said ore-treating furnace, a system of tanks arranged and adapted to receive the sulfurous gases exhausted from said furnace by said exhaust-blower, and a pipe connecting said exhaust-blower with said system of tanks, substantially as described.

In testimony whereof I affix my signature in presence of two witnesses.

ARON M. BEAM.
